UNITED STATES PATENT OFFICE.

ALFRED G. OLSEN, OF ELKHORN, WISCONSIN.

CONCRETE-MIXER.

1,221,368.

Specification of Letters Patent.

Patented Apr. 3, 1917.

Application filed February 6, 1915. Serial No. 6,583.

To all whom it may concern:

Be it known that I, ALFRED G. OLSEN, a citizen of the United States, residing at Elkhorn, in the county of Walworth and State 5 of Wisconsin, have invented certain new and useful Improvements in Concrete-Mixers; and I do hereby declare the following to be a full, clear, and exact description of the invention, such as will enable others 10 skilled in the art to which it appertains to make and use the same.

This invention relates to improvements in the double drum type of concrete mixers, and has for its primary object the simple 15 and efficient control of concrete both in its retention in the respective drums and in its delivery from one to the other.

A further object is the effective control and 20 coöperative delivery of water to the moistening drum at the time of delivery of the dry-mixed concrete thereto.

With these and further objects in view, the invention comprises certain novel constructions, combinations and arrangements 25 of parts as will be hereinafter specified and claimed.

In the accompanying drawings,—

Figure 1 is a side elevation of a machine embodying the features of the present invention.

Fig. 2 is a vertical section through the drums, parts being seen in elevation.

Fig. 3 is a fragmentary, plan view.

Fig. 4 is a perspective view of the movable chute and connected parts detached.

Referring to the drawings by numerals, 1 indicates a supporting frame-work on which is mounted the power plant 2 which may be an internal combustion engine or 40 other motor as preferred. Journaled on rollers 3, 3, mounted in said frame-work, are the mixing drums 4 and 5. Drum 5 is provided with a peripheral sprocket 6 engaged and driven by a sprocket chain 7 which 45 in turn is driven by gearing actuated from the power plant. The intake end of drum 4 is closed except for the axial intake opening 8, and into the opposite end of the drum extends the larger end of drum 5. Drum 4 is 50 preferably cylindrical while drum 5 is in the form of a truncated cone, tapering away from drum 4, and at the inner end of drum

5, that is the larger end, the drum is partially closed by a funnel-like flange 9 having the intake opening 10.

A socket 11 is fixed in frame 1 in an upright or vertical position, and journaled in the socket is a shaft 12. The shaft 12 is bent or curved from the vertical to extend horizontally, and is also curved longitudinally 60 from the beginning of its horizontal portion so as to have its free end extending into the opening 8, the socket 11 being disposed at a point spaced in front of approximately the median line of drum 4, so that the free end 65 of shaft 12 may swing readily into and out of the drum. Shaft 12 carries a water supply tank 13, and the shaft is tubular at least for that portion of its length extending from the tank 13 to its free end so as to enable 70 delivery of water from the tank into the parts with which the free end of the shaft may be in communication. Preferably, the connection between tank 13 and shaft 12 is 75 valved, as at 14, for controlling the delivery of water.

Fixed to the shaft 12 substantially at the free end thereof is a chute 15 consisting of a plate having laterally turned sides 15', 15'', and having its body set at an incline to the 80 horizontal axis of that portion of shaft 12 on which the chute is mounted. The inclination of the chute is such and its vertical dimension proportioned so that when the lower inner edge of the chute lies in communication with the opening 10, the upper outer edge lies approximately at the opening 8. A sleeve 16 is fixed to shaft 12 just outside of the chute 15, and has its inner 85 end portion beveled to correspond with the inclination of the chute, so that the said sleeve affords a stiffening support for the chute, the sleeve being formed with an inner flange 16' riveted or otherwise fixed to the lower portion of the chute. The outer end 90 portion of the sleeve 16 is flanged, as at 16'', and mounted on the shaft 12 is a disk 17 engaging the outer end of and fixed to sleeve 16. The upper edge of disk 17 is bolted or otherwise fixed to the upper edge of chute 15 for aiding in supporting the same. The disk 17 is designed to act as a door, and is 95 in the shape of a disk merely because the openings 8 and 10 are circular.

- When disk 17 is in position for closing the wet mixing drum, the chute 15 is wholly within the said drum, whereby the chute is caused to assist as a deflector in mixing the material in this drum while the disk prevents entrance of additional material.
- The drum 4 is provided with appropriate baffle plates 18 for lifting up contained concrete and tumbling it within the drum from an elevated point down across the drum. Drum 5 is also provided with plates, such as indicated at 19, for engaging concrete and directing the same along the drum toward the discharge end thereof.
- 15 A fixed chute 20 is arranged just outside of and extends slightly into the intake or charging opening 8, the chute being sustained on appropriate brackets 21 fixed to the frame 1.
- 20 In operation, the door 17 being at its innermost position and closing the intake opening 10 for drum 5, the operator delivers a charge of dry concrete to drum 4, as by shoveling the same through the opening 8.
- 25 Power is then delivered for rotating the drums, and this operation continues until the dry concrete material has been thoroughly mixed. Thereupon the operator swings the free end of shaft 12 outward by grasping any appropriate portion of the shaft or its connections and moving the same upon the pivot of the shaft in its socket. The door 17 is thus brought to a position closing opening 8, and the chute 15 is located across that portion of the drum 4 between the inner end of the contracted portion or funnel 9 and the opening 8 so as to receive the falling portions of concrete material as they are discharged from the baffles 18 in the elevated position and are descending across the drum. It will be particularly observed that the incline of the funnel or contracted portion 9 is such that in extending across a portion of the inclosure of drum 4, the said funnel has its inclined wall disposed at all times for directing concrete material falling thereon down into contact with chute 15 whenever the chute is in its outer position. By this means a chute 15 of minimum size may be employed, as it is not necessary for the chute to extend for the full width of drum 4, but only for that portion thereof between the inner end of the frusto-conical or funnel-like portion 9 of drum 5 and the opposite side of drum 4. The operation of delivering the dry mix to chute 15 continues as long as any of the concrete material remains in drum 4, and all of the material is thus delivered through the opening 10 into drum 5. At the time the chute 15 is moved to the concrete delivering position, the operator opens the supply of water to the tubular portion of shaft 12 so that as the concrete enters drum 5 the water enters with it flowing in the same direction of travel as

the concrete so that the best possible opportunity is afforded for thoroughly and effectively moistening the concrete. The concrete is gradually fed by the blades 19 to the discharge end of drum 5 from which the concrete is delivered to any appropriate vehicle for transportation to the point of use or for other disposal. The supplying of water may be accomplished either by having the tank 13 filled and opening valve 14 to the extent required for feeding the water at the rate desired, or the valve can be left open and water supplied to tank 13 through a hose or otherwise at the rate desired.

The discharge end of drum 5 is normally closed by a funnel-shaped cap or cover 22 which snugly fits the open end of the drum, and which has its outer end tapered to an axial shaft journaled in a sleeve 23 and keyed thereto so as not to accidentally fall out of the sleeve. The sleeve 23 is carried by a pair of arms 24 which form a bail-like support and extend on opposite sides of the cap to points of pivotal supports 25, 25, at the upper ends of brackets 26, 26, which are fixed to and upstand from frame 1 on a lateral incline at opposite sides of drum 5. When concrete is being delivered from drum 4 to drum 5, the cap 22 is positioned for closing the discharge end of drum 5, the cap remaining in its closed position by the force of gravity, as the pivot points 25 are above the cap when in its closed position, and the cap revolves freely with the drum so as not to offer frictional resistance. While the operator is removing one load of concrete, the concrete being fed along the drum 5 toward its discharge end will be forced over into the cap 22, and by the time the operator returns approximately a load of concrete will have collected at the discharge end of the drum so that all the operator needs to do is to grasp the sleeve 23 and lifting it upwardly swing the cap to its open position, so that the concrete will be discharged from the cap and from the open end of the drum.

What I claim is:—

1. In concrete mixing apparatus, the combination with a dry mixing drum and a wet mixing drum communicating therewith, of a chute for delivering material from the dry mixing drum to the wet mixing drum, the said chute being movable to and from a position effecting such delivery, the said chute being of less dimension in the direction across the dry mixing drum than the width of said dry mixing drum, and the wet mixing drum being formed with means coöperating with the chute for directing concrete material onto the chute when positioned with its uppermost portion adjacent that wall of the dry mixing drum remote from the wet mixing drum.

2. In concrete mixing apparatus, the combination with a dry mixing drum and a wet

mixing drum communicating with and extending into the dry mixing drum, of a chute for delivering concrete material from the dry mixing drum to the wet mixing drum, the chute being movably mounted and adapted to be moved to and from a position for effecting such delivery and being dimensioned to extend substantially from that wall of the dry mixing drum remote from the 5 wet mixing drum to the portion of the wet mixing drum extending into the dry mixing drum.

3. In concrete mixing apparatus, the combination with a dry mixing drum having an 15 intake opening at one end, a wet mixing drum extending into the other end of the dry mixing drum and having an intake opening within the dry mixing drum, a feeding chute, and a movable support carrying 20 the same and adapted to be moved for shifting the support through the intake opening of the wet mixing drum to and from a position across the dry mixing drum for delivering material from the dry mixing drum to 25 the wet mixing drum.

4. In concrete mixing apparatus, the combination with a dry mixing drum, of a wet mixing drum communicating with one end of the dry mixing drum, a chute movable 30 through the end of the wet mixing drum from within the wet mixing drum to within the dry mixing drum for delivering material from the latter to the former, and a movable shaft sustaining the chute and having its 35 chute engaging portion shiftable through the end of the wet mixing drum.

5. In concrete mixing apparatus, the combination with a dry mixing drum and a wet mixing drum communicating with one end 40 of the dry mixing drum, of a chute movable from within the wet mixing drum through the end thereof to within the dry mixing drum for delivering material therefrom to the wet mixing drum, and a door movable 45 with the chute for closing the wet mixing drum when the chute is disposed therein.

6. In concrete mixing apparatus, the combination with a dry mixing drum and a wet mixing drum communicating with the dry 50 mixing drum, of a shaft extending into the dry mixing drum and movable across the dry mixing drum to the wet mixing drum, and a chute carried by said shaft and movable therewith to and from a position for 55 discharging material from the wet mixing drum into the dry mixing drum.

7. In concrete mixing apparatus, the combination with a dry mixing drum and a wet mixing drum communicating with the dry 60 mixing drum, of a pivotally mounted shaft having its free end extending into the wet mixing drum, and a chute carried by the free end portion of the shaft and movable therewith to and from a position within the dry 65 mixing drum for delivering material from

the dry mixing drum into the wet mixing drum.

8. In concrete mixing apparatus, the combination with a dry mixing drum and a wet mixing drum communicating therewith, of 70 a shaft movably extending into the wet mixing drum, a chute carried by the shaft within the wet mixing drum, and a door carried by the shaft in position for closing the communication with the dry mixing drum, the 75 shaft being movable for shifting the door for opening communication and for shifting the chute to position for directing material from the dry mixing drum to the wet mixing drum.

9. In concrete mixing apparatus, the combination with a dry mixing drum and a wet mixing drum communicating therewith, of 80 a tubular shaft extending into said drum and movable relative thereto, a chute carried by said shaft and adapted to be moved therewith to and from a position for directing material from the dry mixing drum to the wet mixing drum, and means for delivering 85 water through said shaft.

10. In concrete mixing apparatus, the combination with a rotary dry mixing drum and a wet mixing drum carried thereby and communicating therewith, the wet mixing drum having an intake opening into the dry 90 mixing drum and the dry mixing drum having an intake opening co-axial with the intake opening of the wet mixing drum, of an axially shiftable shaft extending through the intake opening of the dry mixing drum, 95 a chute carried thereby and adapted to be moved therewith to and from a position for directing material from the dry mixing drum into the wet mixing drum, and a closure carried by said shaft and adapted at 100 times to close the intake opening of the wet mixing drum and at other times to close the intake opening of the dry mixing drum according to the relative position of the shaft.

11. In concrete mixing apparatus, the combination with a dry mixing drum and a wet mixing drum having its intake end extending into the dry mixing drum and converging therein and forming an inwardly tapering frusto-conical portion, of a chute 110 movably mounted in the wet mixing drum and adapted to be moved into the dry mixing drum and dimensioned to extend from the inner terminus of said frusto-conical portion to adjacent the remote wall of the 115 dry mixing drum for delivering material from the dry mixing drum to the wet mixing drum.

12. In concrete mixing apparatus, the combination with a dry mixing drum and a 120 wet mixing drum communicating therewith, of a permanently inclined movably mounted chute adapted to move from within the dry mixing drum to within the wet mixing drum and from the wet mixing drum to within the 130

dry mixing drum for being adjusted to and from a position for effecting delivery from the dry mixing drum to the wet mixing drum, and a movable support for the chute 3 adapted to be shifted for moving the chute to a position wholly within the wet mixing drum.

In testimony whereof I affix my signature in presence of two witnesses.

ALFRED G. OLSEN.
